UNITED STATES PATENT OFFICE.

CHARLES S. FERGUSON, OF BROOKLYN, NEW YORK.

CAR-COUPING DEVICE.

1,233,999.

Specification of Letters Patent. Patented July 17, 1917.

Application filed November 2, 1915. Serial No. 59,258.

To all whom it may concern:

Be it known that I, CHARLES S. FERGUSON, a citizen of the United States, residing at Brooklyn, in the county of Kings and State 5 of New York, have invented new and useful Improvements in Car-Coupling Devices, of which the following is a specification.

This invention relates to car coupling devices and more particularly to draw bars or 10 beams.

In using the present type of bar the strain of moving an entire train is placed upon a single draw bar which causes considerable wear and lost motion in the draw head rig- 15 ging, springs, strap etc; and obviously risks the draft timbers tearing out, or draw bar coming loose. It is the object, therefore, of this invention to obviate these difficulties and to avoid many similar difficulties inher- 20 ent in the present type of draw bar.

It is another object of this invention to provide a coupling means between the cars in which the draw bar or beam of each car has only the strain exerted thereon incident 25 to overcoming the inertia of its own car and further in which all of the cars are connected as by a series of links connected together by the coupler head.

Further objects of the invention will ap- 30 pear as the following description is read in connection with the accompanying drawing, which forms a part of this application, and in which:—

Figure 1 is a top plan view of the coupling 35 device showing the same applied to a car, the car body being shown in dotted lines.

Fig. 2 is a side elevation of the coupling device, showing the same resting upon the car bolsters.

Fig. 3 is a top plan view of a modified 40 form of the invention, showing the same applied to a car having a center sill, the body of the car being shown in dotted lines.

Fig. 4 is a view in elevation of a modified 45 form of the invention, and showing the same resting upon the car bolsters.

Referring more particularly to the drawing, 1 represents the car body which has secured thereto the large end bolsters 2. These 50 bolsters have mounted adjacent the center thereof the guide brackets 3 between which is slidably mounted the draw bar 4 preferably an I beam and receiving between the flanges thereon extensions on the brackets 3. This draw bar extends the full length of the

car, as shown, and has its terminals downwardly bent, as indicated at 5, and attached thereto are the coupler mounting members 6, upon which the coupler heads 7 are removably pivoted. The draw bar 4 has secured to 60 the web portion thereof adjacent each down-turned end a pair of plates 8 which are spaced from the guide brackets 3 and provided with offset portions between which and the extending portions on the guide 65 brackets are arranged springs 9, lying between the flanges on the draw bar and serving to take up the shock when coupling and to remove the strain from the car in starting and stopping.

Where the car is provided with a center sill such as is shown in Figs. 3 and 4, draw bars 10 corresponding in shape to the draw bar 4 are arranged upon opposite sides of the sill and have their ends connected together at opposite ends of the car by yoke-shaped coupling head supports 11. In this instance the guide brackets 12 and plates 13 are located upon the inner sides of each bar, and have interposed between them the 80 springs 14. It is, of course, understood that the springs may be either compression or expansion springs, and that as many may be used as are found desirable.

In the forming it will be seen that when a 85 train is made up that each car carries its draw bar which is slidably mounted thereon and, therefore, in a sense is independent of the car body so that in case any one of the cars should break in two the cars behind 90 would still be connected to the engine through the draw bars.

Not only is the foregoing difficulty obviated but the springs which are now employed may be considerably lightened. In 95 the present construction the springs must be strong enough on each draw bar to pull a whole train, while with the present construction the springs for each draw bar only have to move the car to which they are attached, thus avoiding the inherent defect in the present system of shocks in starting and stopping, which proportionately increase from the first car started to the last car started and vice versa in stopping.

What is claimed is:—

In a device of the class described, the combination with the bolsters of a car, a draw bar movable thereon and having flanges thereon, guide members on said bolsters ex- 110

tending between the flanges on the draw bar,
plates secured to said draw bar between said
flanges and having offset portions spaced
from said guide members, and springs ar-
5 ranged between the flanges on said draw bar
and engaging said guide members and
plates.

In testimony whereof I affix my signature
in presence of two witnesses.

CHARLES S. FERGUSON.
